UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS HEATING-STOVE.

SPECIFICATION forming part of Design No. 30,060, dated January 24, 1899.

Application filed December 5, 1898. Serial No. 698,379. Term of patent 14 years.

To all whom it may concern:

Be it known that I, LAZARD KAHN, a citizen of the United States, residing in Hamilton, Butler county, Ohio, have invented and 5 produced a new and original Design for Gas Heating-Stoves, of which the following is a specification, reference being had to the accompanying drawing, forming a part thereof.

The drawing is a perspective view of a gas 10 heating-stove, showing my new design.

As shown in the drawing, the leading or material feature of my design consists of a

rectangular shape for the body A and high slim legs C, forming downward prolongations at the corners B of the box.

Having described my invention, what I claim as new, and desire to secure by Letters Patent, is—

The design for a gas heating-stove, as herein shown and described.

LAZARD KAHN.
